(57) **CLAIM**

The ornamental design for an external catheter, with covers, for a female user, as shown and described.

DESCRIPTION

FIG. 1 is a side view of the external catheter, with covers, for a female user.

FIG. 2 is a top view of the external catheter, with covers, for a female user.

FIG. 3 is a front view of the external catheter, with covers, for a female user; and,

FIG. 4 is a perspective view of the external catheter, with covers, for a female user.

The features shown in broken lines depict environmental subject matter only and form no part of the claimed design.
